BROACHING MACHINE

Hugh C. Nye, Detroit, Mich., assignor to Vickers
Incorporated, Detroit, Mich., a corporation of
Michigan

Application February 23, 1938, Serial No. 192,027

14 Claims. (Cl. 90—33)

This invention relates to power transmissions and more particularly to those of the fluid type wherein a power transmission fluid, such as oil, and hereinafter referred to as such, is utilized 5 for the transmission of power between one or more pumps and one or more fluid motors.

The invention is particularly concerned with a power transmission system particularly adapted for operating a plurality of hydraulic motors in 10 predetermined sequence and may be used for example on a hydraulically operated broaching machine. In the art of surface broaching it is common to utilize a pair of oppositely moving broaching tools or rams, one of which performs 15 a broaching stroke while the other simultaneously returns to starting position. Machines of this character are frequently provided with automatic loading fixtures which position a working piece in front of one tool and after the broaching stroke is completed shifts to remove that finished work piece and to place to new work piece in front of the other broaching tool, which, in the meantime, has returned to starting position. It is frequently desirable in certain types 20 of broaching work to provide also automatic clamping means for positively holding the work piece in position during broaching.

It is an object of the present invention to provide a hydraulic power transmission system, particularly adapted for the automatic operation of 25 a broaching machine of the character described with improved reliability, safety and economy of operation.

Further objects and advantages of the present 30 invention will be apparent from the following description, reference being had to the accompanying drawings wherein a preferred form of the present invention is clearly shown.

In the drawings:

Figure 1 is a diagrammatic view showing a 35 hydraulic circuit embodying a preferred form of the present invention.

Figure 2 is a top view of a broaching machine in which the transmission system of the present 40 invention may be incorporated.

Figure 3 is a front view of the broaching machine of Figure 2.

An electric motor 10 is directly connected to 45 operate three pumps, 12, 14 and 16, which have suction conduits 18, 20 and 22 through which oil may be withdrawn from a tank 24. Pump 12 has a delivery conduit 26 in which is inserted a relief valve 28 for by-passing oil to the tank through conduit 30 whenever a predetermined 50 pressure is exceeded in the conduit 26 and also

whenever the control chamber 32 of the valve 28 is vented. The relief valve illustrated is similar to that shown in the Patent #2,043,453 to Harry F. Vickers. The conduit 26 connects to a pressure responsive, back pressure valve 34 adapted 5 to open communication between a chamber 36 and a port 38 whenever a predetermined pressure is exceeded in the chamber 36.

Communicating with the port 38 is conduit 40, leading to the pressure port of a conventional 10 servo-operated, closed center, four-way valve 42. A conduit 44 connects the tank port of the valve 42 with the tank 24. The cylinder ports of the valve 42 connect by conduits 46 and 48, with the opposite ends of a cylinder 50. The latter has 15 a piston 52 reciprocably mounted therein and connected with a rod 54 extending through both ends of the cylinder 50. The rod 54 may be operably connected to a suitable loading fixture for loading and unloading work pieces at the 20 working stations in line with the broaching tools.

Pump 14 has a delivery conduit 56 in which is inserted a relief valve 58 having a control chamber 60 and of similar construction to the valve 28. The conduit 56 extends to the pressure port of a servo operated, four-way valve 62 which has its tank port connected by a conduit 64 with the tank 24. The cylinder ports of the valve 62 are connected by conduits 66 and 68 with the head ends of a pair of cylinders 70 and 72. The latter carry reciprocable pistons 74 and 76 having rods 78 and 80, to which suitable surface broaching tools may be attached. The rod ends of the cylinders 70 and 72 are connected together by a conduit 82. A branch conduit 84 extends to the discharge conduit 86 of the pump 16. A manual shut-off valve 88 is interposed in the conduit 84 while a relief valve 89 serves to relieve oil from conduit 84 to the tank if the pressure therein gets too high.

The discharge conduit 86 of the pump 16 has interposed therein a relief valve 87 which may be similar in construction to the back pressure valve 34 and which discharges oil to the tank through a conduit 90 whenever a predetermined 45 pressure is exceeded in the conduit 86. The conduit 86 has two branches 92 and 94 which communicate with the pressure ports of a pair of spring biased servo-operated, four-way valves 96 and 98. Tank connections to these valves are 50 established by the conduits 100 and 102 while the cylinder ports are connected to opposite ends of cylinders 104 and 106 by conduits 108, 110, 112 and 114. The cylinders 104 and 106 carry pistons 116 and 118, the rods 120 and 122 of which 55

are adapted to operate suitable clamping means associated with the loading mechanism.

In order to cause the various pistons 52, 74, 76, 116 and 118 to operate through a predetermined sequence of movements there are provided a series of pilot valves operated by the various pistons and which are connected by various pilot circuits to the operating chambers of the servo operated valves 42, 62, 96 and 98.

10 For the purpose of controlling operation of valve 42, a pilot valve 124 is provided, which is shown as a rotary four-way valve, having ports P, T, 1 and 2. The valve may be shifted between a position in which port P is connected to port 1, and port T is connected to port 2 and a second position 45° away clockwise, in which port P is connected to port 2, and port T connected to port 1. A conduit 126 connects from the delivery conduit 92 to the port P of valve 124. Port T is connected to tank by a conduit 128. Port 1 is connected by a conduit 130 to the left hand operating chamber of the valve 42 while port 2 is connected by a conduit 132 to the right hand operating chamber of the valve 42.

15 The control chamber 32 of relief valve 28 is connected by a conduit 134 with a pilot valve 136 having a plunger 138 actuatable by a cam 140 carried on the rod 54. When the plunger 138 is depressed communication is established between the conduit 134 and a conduit 142. When the plunger is released it moves upwardly to close such communication.

20 The conduit 142 connects to the port P of a rotary pilot valve 144, similar in construction to the valve 124, and operable therewith through a common operating shaft. The port T connects by a conduit 146 with the tank. Port 1 connects by a conduit 148 with the port P of a rotary pilot valve 150. Port T of valve 150 connects to a conduit 152 while ports 1 and 2 connect by conduits 154 and 156 with the ports 1 and 2, respectively, of a rotary pilot valve 158. Port P of the latter is plugged while port T is connected to tank through a conduit 160.

25 The port 2 of valve 144 is connected by a conduit 162 to the port P of a rotary pilot valve 164. Port T of the latter connects by a conduit 166 with the tank while ports 1 and 2 are connected by conduits 168 and 170 with the ports 1 and 2 respectively of a rotary pilot valve 172. The port P of the latter is plugged while port T is connected by a conduit 174 to the tank.

30 A rotary pilot valve 176 has its port P connected to the pressure conduit 92 by a conduit 178 and its port T connected to tank by a conduit 180. Ports 1 and 2 are connected by conduits 182 and 184 to the ports 2 and 1, respectively, of a rotary pilot valve 186. The latter is connected by a common operating shaft to the pilot valve 172 and has its port T plugged while its port P connects by a conduit 188 with the operating chamber of the valve 96.

35 A rotary pilot valve 190 has its port P connected to the conduit 92 by a conduit 192 and its port T to tank by a conduit 194. Ports 1 and 2 of the valve 190 connect by conduits 196 and 198 with the ports 2 and 1, respectively, of a rotary pilot valve 200. The latter is connected by a common operating shaft to the pilot valve 172 and has its port T plugged and its port P connected by a conduit 202 with the operating chamber of the valve 98.

40 The control chamber 60 of the relief valve 58 is connected by a conduit 204 with a port 206 of a plunger type pilot valve 208. A port 210

45 connects by a conduit 212 with a port 214 of a plunger type pilot valve 216 identical to the valve 208. A port 218 connects by a conduit 220 to tank. The valve 208 has a port 222 connected by a conduit 224 with the pressure conduit 92 and a port 226 connected by a conduit 228 with the right hand operating chamber of the valve 62. The valve 216 has a port 230 connected by a conduit 232 to the pressure conduit 92 and also has a port 234 connected by a conduit 236 with the left hand operating chamber of the valve 62. The valves 208 and 216 have tank ports 238 and 240 connected to tank by conduits 242 and 244.

50 A pair of rotary pilot valves 246 and 248 have their ports P and 2 plugged and their ports T connected to tank by a conduit 250. Port 1 of valve 246 connects by a conduit 252 to the conduit 204, leading from the control chamber of the relief valve 58. Valve 248 has its port 1 connected by a conduit 254 to the conduit 134 leading from the control chamber of the relief valve 28.

55 The valves 150, 158, 164, 172, 176 and 190 each have a drain port D which is connected to tank for the purpose of draining leakage at the end chambers of the valve. Valves 124 and 144 are operated by a forked trip lever 256 which is actuated clockwise by a trip 258 on the stem 54 when the latter reaches the right hand limit 30 of its movement. The lever 256 is operated counter clockwise by a trip 260 when the stem 54 reaches the left hand limit of its movement. Valve 176 is operated by a star wheel 262 clockwise $\frac{1}{8}$ of a revolution each time the rod 54 moves toward center position while traveling to the right. For this purpose a latch trip 264 is carried by the stem 54 which is ineffective on leftward movement of the stem 54. The valve 190 is operated by a star wheel 266 and is operated in an analogous manner in the opposite direction by a latch trip 268 also carried by the rod 54. The plungers of the valves 208 and 216 are adapted to be depressed by the rods 122 and 120 when the latter reach their fully projected 45 position to the right and left respectively. When the plunger of valve 208 is up, as illustrated, port 208 is in communication with port 210 while port 222 is blocked and port 226 is connected to port 238. When the plunger is depressed ports 206 and 210 are blocked while port 226 is cut off from port 238 and connected with port 222. Similar connections are established in the valve 216 when the same is operated by the rod 120.

60 Valves 150 and 164 are operated by star wheels 270 and 272 which in turn are actuated by latch trips 274 and 276 carried by the rods 120 and 122. The construction is such that star wheels are given $\frac{1}{8}$ of a revolution of movement of just prior to the time when the stem reaches its fully 60 retracted position.

65 Valves 172 and 186 are operated by a star wheel 278 which in turn is actuated counter clockwise $\frac{1}{8}$ of a revolution by a latch trip 280 carried by the rod 80. The star wheel is actuated as the 65 rod 80 reaches the lower limit of its movements. Valves 158 and 200 are correspondently actuated by a star wheel 282 and latch trip 284 carried by the rod 78.

70 Referring now to Figures 2 and 3, there is illustrated diagrammatically a dual ram broaching machine representing an example of the character of machine in which the present hydraulic circuit may be used. The machine comprises a main frame having a horizontal table portion 286 75

and an upstanding back frame 288. The portion 288, is formed with a pair of guideways 290 and 292 in which are mounted reciprocable slides 294 and 296; the latter are adapted to have suitable 5 surface broaching tools such as indicated at 298 removably secured thereto. The slides 294 and 296 are fastened at their lower ends by backwardly extending brackets, not shown, to the piston rods 78 and 80 respectively. The table 10 portion 286 carries a pair of horizontal guideways 300 and 302 on which are reciprocably mounted a pair of work positioning slides 304 and 306, the latter having suitable recesses 308 and 310 in which the work piece, to be broached, 15 may be positioned. The slides 304 and 306 are adapted to be alternately reciprocated inwardly and outwardly in the well known manner to position work pieces in front of each broaching tool 298 at the start of the broaching stroke and 20 remove the finished work at the completion thereof. A suitable hopper feed, not shown, may be provided for automatically loading the recesses 308 and 310 as they are retracted to their outer 25 position.

25 The piston rod 54 is arranged to actuate the slides 304 and 306 in the sequence required by any suitable mechanism. In the construction illustrated, the slides 304 and 306 are provided with extension arms 312 and 314 which lie in the path 30 of collars 316 and 318 rigidly secured to the rod 54. The extensions 312 and 314 are also connected by toggles 320 and 322 to stationary brackets 324 and 326 secured to the main frame. The rod 54 carries a pair of cams 328 and 330 35 which are adapted to depress the center pivot of the toggle 322, for example, as the rod 54 moves to the right from its central position and thus "break" the toggle 322.

35 The rod 54 also carries a pair of cams 332 and 40 334 which are adapted to lift the center pivot of the toggle 320, for example, as the rod 54 moves toward center position from its right hand position. Suitable compression springs 336 and 338 yieldingly maintain the center pivot of the 45 toggles in the path of movement of the cams 332 and 334. Suitable clamping means may be provided, comprising arms 340 and 342, carried on shafts 344 and 346 pivoted in brackets 348 and 350. The shafts 344 and 346 carry downwardly 50 extending arms 351 and 352 which are connected to the piston rods 122 and 120 respectively.

55 The operation of the machine disclosed will be apparent from the foregoing description from which will be seen that, starting with the parts 55 in the position shown in the drawing wherein the slide 296 just completed a broaching stroke while the slide 294 has just completed a return stroke and the clamps 340 and 342 are both released. If the rod 54 be moved to the right, the 60 cam 330 breaks the toggle 322 and thereafter the collar 318 abuts the extension 314, forcing the slide 306 to the right and removing the finished work piece in the recess 310 from the position in front of the tool slide 296. If now the rod 54 be returned leftwardly to center position the cam 65 332 will engage the center pin of the toggle 320, forcing the same upwardly and causing the slide 304 to be moved to the left. A fresh work piece which was previously positioned in the recess 308 70 is thus presented in front of the tool slide 294. The work piece may be clamped by moving the piston rod 122 to the right whereupon the apparatus is ready to perform a broaching stroke by moving the slide 294 downwardly.

75 It will be noted that on the leftward movement

of the piston rod 54 the under surface of the cam 332 will engage the center pin of the toggle 320, forcing the same downwardly a slight amount against the spring 336. As soon as the cam 332 passes the toggle pin the latter moves upwardly 5 again under the urge of spring 336 so that the pin will again lie in the path of the upper surface of the cam 332 on its leftward movement. At the completion of the broaching stroke of the 10 slide 294, the slide 296 is returned to its upper position and a similar cycle may be repeated except that the rod 54 moves to the left and returns to center pushing the slide 304 back to the left and returning the tool slide 296. Thereafter the 15 clamp 342 may be operated and a broaching cycle performed at the slide 296.

20 In operation of the hydraulic transmission system, starting with the parts in the position shown in the drawing, in which the right hand broaching piston 76 has just completed a broaching stroke and the left hand piston 74 just completed a return stroke, the clamping pistons 116 and 118 are both in released position and the piston 52 is in center position having reached that 25 position by a rightward movement during which the fixture for the right hand broach was loaded. With the motor 10 in operation, fluid is delivered by the pump 16 to the conduits 86, 92 and 94 and valves 96 and 98 and conduits 110 and 112 to the rod ends of cylinders 104 and 106 thus maintaining 30 pressure thereon while excess fluid passes over the relief valve 87. Fluid supplied by the pump 16 is thus available for all of the pilot 35 circuits.

With the valves 246 and 248 in the position shown, that is the "run" position, the relief valve control chambers 32 and 60 are blocked at ports P of these valves so that, unless vented through other paths, the valves 28 and 58 will close. Valve 58 is at this time, however, vented through the 40 conduit 204, ports 206 and 210 of valve 208, conduit 212, ports 214 and 218 of valve 216 and conduit 20 to tank thus permitting oil to by-pass from the pump 16 through conduit 56 and valve 58 to the tank. The main ram pistons 74 and 76 45 accordingly remain stationary. The other venting path for the relief valve 28 is blocked however. This path may be traced through the conduit 134, valve 136, conduit 142, ports P and 1 of valve 144, conduit 148, ports P and 2 of valve 150, conduit 156, ports 2 and P of valve 158, the latter 50 of which is plugged. Pressure accordingly builds up in the conduit 26 sufficiently to open back pressure valve 34, so that pressure oil is delivered through conduit 40, valve 42 to the left hand 55 end of cylinder 50, thus causing piston 52 to move to the right for unloading the finished work piece from the right hand side of the machine. Oil discharged from the right hand end of cylinder 50 returns through conduit 46, valve 42 and conduit 44 to the tank. As soon as the piston 52 has 60 started this movement, cam 140 rides off, plunger 138 closes the valve 136 and thus insures that the vent path for the relief valve 28 remains 65 blocked thereafter.

As the piston 52 reaches the end of its rightward stroke, trip 258 actuates forked lever 256 clockwise, shifting the valves 124 and 144 to reverse their connections. The valve 42 is accordingly shifted by pilot pressure transmitted 70 through conduit 126, ports P and 2 of valve 124 and conduit 132 to the right hand operating chamber of valve 42. Fluid returns from the left hand chamber through conduit 130, ports 1 and T of valve 124 and conduit 128 to the tank. Pres- 75

sure oil from the pump 12 accordingly is admitted to conduit 46 and the right hand end of cylinder 50 causing the same to move to the left for the purpose of loading the left side of the machine.

Just before piston 52 reaches its central position, latch trip 268 shifts star wheel 266 and valve 190 to establish a pilot circuit for operation of the valve 98. This circuit is from conduit 92 through conduit 192, ports P and 1 of valve 190, conduit 196, ports 2 and P of valve 200 and conduit 202 to the operating chamber of valve 98. The latter accordingly shifts to the left against its spring bias admitting pressure oil from the conduit 94 to the conduit 114 causing the piston 118 to move to the right for clamping the work in the left hand side of the machine.

As the piston 52 reached central position the cam 140 depressed the plunger 138 of valve 136 opening communication from the control chamber 32 of valve 28, through conduit 134, valve 136, conduit 142, ports P and 2 of valve 144 (which was previously shifted), conduit 162, ports P and 2 of valve 164, conduit 170, ports 2 and T of valve 172 and conduit 174 to tank. Valve 28, accordingly, opens thus by-passing the delivery of pump 12 at zero pressure.

As the clamping piston 118 reaches the outer limit of its stroke, the plunger of valve 208 is depressed, blocking the vent circuit for valve 58 and opening the pilot circuit for operation of valve 62. The vent conduit 204 is blocked at the ports 206-210 of the valve 208. The pilot circuit is established from conduit 92 through the conduit 224, ports 222 and 226, and conduit 228 to the right hand operating chamber of the valve 62 thus shifting the latter to the left and admitting pressure oil from the pump 14, through conduit 56, relief valve 58 which is now closed, valve 62 and conduit 66 to the head end of cylinder 70. Piston 74 accordingly descends, forcing oil out of the rod end of cylinder 70 through the conduit 82 to the rod end of cylinder 72. Piston 76 is accordingly caused to be returned to the top simultaneously with the downward movement of the piston 74. Oil discharged from the head end of cylinder 72 returns to tank through the conduit 68, valve 62 and tank conduit 64.

As the rod 78 reaches the lower limit of its movement, latch trip 284 actuates star wheel 282 and valves 158 and 200 to reverse the connections thereof. Reversal of valve 200 relieves the pressure from the operating chamber of valve 98 and permits the valve to return to its right hand position, discharging oil through conduit 202, ports P and 1 of valve 200, conduit 198, ports 2 and T of valve 190 to conduit 194 to the tank. Pressure oil from the pump 14 accordingly passes from the conduit 94 through valve 98 to the conduit 112 and the rod end of cylinder 106 thus moving piston 118 to the left for unclamping the work at the left side of the machine. As the piston 118 starts to the left the plunger of valve 208 is released thus again opening the vent circuit 204 for the relief valve 58 and at the same time cutting off port 226 from port 222 and connecting the former to the tank port 238. The valve 62 does not shift at this time, however, since a pressure connection is not yet established to the left hand operating chamber thereof. The valve 58 opens due to venting of the control chamber 60 thus by-passing the discharge of pump 14 at no pressure. The broaching pistons 74 and 76 accordingly remain stationary.

As the piston 118 approaches the left limit of

its stroke, latch trip 276 actuates star wheel 272 clockwise to reverse connections in the valve 164, connecting port P with port 1 and port T with port 2. The vent circuit for valve 28 is accordingly blocked by this shift since the chamber 32 is now in communication through conduit 134, valve 136, conduit 142, ports P and 2 of valve 144, conduit 162, ports P and 1 of valve 164, conduit 168, port 1 of valve 172 with port P thereof which is blocked.

With the valve 42 remaining in its left hand position, to which it was previously moved, pressure builds up in the conduit 26 and oil passes through valve 34, conduit 40, valve 42, and conduit 46 to the right hand end of cylinder 50 causing the same to move to the left for the purpose of unloading the left side of the machine. As the piston 52 starts its movement, plunger 138 is released by cam 140 thus insuring that the vent circuit for valve 28 is maintained blocked.

As the piston 52 approaches the left limit of its stroke, trip 260 actuates the forked lever 256 clockwise thus shifting valves 124 and 144 to the position shown in the drawings. Valve 124 establishes a pressure connection through conduit 126, ports P and 1 of valve 124 and conduit 130 to the left end of valve 42 thus shifting the same to the right and reversing pressure and tank connections to the cylinder 50. Piston 52 accordingly returns to the right toward center position and as the latter is reached, cam 140 depresses plunger 148 thus opening a vent connection for the valve 28, which connection is made by the new position of valve 144. This circuit is from the control chamber 32 through conduit 134, valve 136, conduit 142, ports P and 1 of valve 144, conduit 148, ports P and 2 of valve 150, conduit 156, ports 2 and T of valve 158 and conduit 160 to the tank. Relief valve 28 accordingly opens, by-passing the delivery of pump 12 and stopping the piston 52 in its central position.

As the piston 52 approached central position, moving to the right, latch trip 264 actuated the star wheel 262 counterclockwise, shifting valve 176 to establish a pilot circuit for actuating the valve 96. This circuit is from the pressure conduit 92, through conduit 178, ports P and 2 of valve 176, conduit 184, ports 1 and P of valve 186 and conduit 188, to the actuating chamber of valve 196. The latter shifts to the left against its spring bias connecting pressure oil delivered from the pump 14 through the conduits 86 and 92, valve 96, and conduit 108, to the head end of cylinder 104. Piston 116 accordingly moves to the left to clamp the work in the right side of the machine.

As the piston 116 approaches the end of the stroke, rod 120 depresses the plunger of valve 216, blocking the vent for relief valve 58 at the ports 214 and 218 and establishing a pressure connection through conduit 232, port 230, port 234 and conduit 236, to the left hand operating chamber of the valve 62, shifting the same to the right. Relief valve 58 closes causing oil pressure to build up in conduit 56 which is transmitted through the valve 62 and conduit 68 to the head end of cylinder 72 forcing the piston 76 downwardly. The piston 74 ascends simultaneously, discharging oil from the head end of cylinder 70 through conduit 66, valve 62 and conduit 64 to the tank. The work piece at the right hand side of the machine is accordingly broached while the left hand side of the machine performs its return stroke. When rod 80 approaches its lowest position trip 280 actuates star wheel 278 counterclockwise, shifting valves 186 and 172.

The valve 96 is accordingly permitted to return to the right under its spring bias, discharging oil through conduit 188, ports P and 2 of valve 186, conduit 182, ports I and T of valve 176 and conduit 180 to the tank. Pressure oil from the pump 16 is accordingly admitted through conduit 92, valve 96 and conduit 110 to the rod end of cylinder 104, unclamping the work at the right side of the machine. At the beginning of this stroke, the plunger of valve 216 is released thus again opening the vent circuit for relief valve 58 through conduit 204, ports 206 and 210 of valve 208, conduit 212, ports 214 and 218 and valve 216 and conduits 220 and 244 to tank. Relief valve 15 58 accordingly opens, by-passing the discharge of pump 14 and permitting the broaching pistons to remain stationary in the position illustrated.

As the end of the stroke of piston 116 is reached, latch trip 274 actuates star wheel 270 counter-clockwise, shifting the valve 150 and again blocking the vent circuit for relief valve 28. This circuit is now from chamber 32, through conduit 134, valve 136, conduit 142, ports P and I of valve 144, conduit 148, ports P and I of valve 25 150, conduit 154, and port I of valve 158 to the port P which is plugged.

The same cycle of operations which has just been described is accordingly repeated. There is a difference in the second cycle, however, in 30 that all of the star wheel operated valves are oppositely connected at any phase of the cycle to the connection which existed during the first cycle. At the end of the second complete cycle the third cycle repeats with the star wheel valves going through the same sequence as occurred in 35 the first cycle.

When it is desired to stop the continuous operation of the machine, the valves 246 and 248 may be shifted to connect port I with port T of 40 each, thus venting both the relief valves 28 and 58 through the conduits 254 and 252 respectively. When this is done, the discharge of both pumps 12 and 14 is by-passed and the machine will stop at any point in the cycle, except during a clamping or unclamping sequence.

While the form of embodiment of the invention as herein disclosed, constitutes a preferred form, it is to be understood that other forms might be adopted, all coming within the scope of the 50 claims which follow.

What is claimed is as follows:

1. A hydraulic power transmission system for operating a dual ram broach having a pair of power operated broach slides, a power operated 55 loading and unloading device operable on two separate forward strokes to respectively load a work piece at one slide and unload a work piece at the other slide, and on two separate reverse strokes to respectively load and unload work pieces at the opposite slides, and power operated clamping means at each slide, comprising in combination, pumping means, a broaching motor, a pair of clamping motors and a loading and unloading motor, means for controlling the supply of fluid to said motors, and an operating system for said control means to provide a continuous cycle of loading, clamping, broaching, unclamping and unloading at each slide alternately.

2. A hydraulic power transmission system for 70 operating a dual ram broach having a pair of power operated broach slides, a power operated loading and unloading device operable on two separate forward strokes to respectively load a work piece at one slide and unload a work piece at the other slide, and on two separate reverse

strokes to respectively load and unload work pieces at the opposite slides, and power operated clamping means at each slide, comprising in combination, pumping means, a broaching motor, a pair of clamping motors and a loading and unloading motor, means for controlling the supply of fluid to said motors, and an operating system for said control means to provide a continuous cycle of loading, clamping, broaching, unclamping and unloading at each slide alternately, 10 said operating system including interlocking means for initiating operation of each motor only when the other motors have completed their intended operations.

3. A hydraulic power transmission system for 15 operating a dual ram broach having a pair of power operated broach slides, a power operated loading and unloading device operable on two separate forward strokes to respectively load a work piece at one slide and unload a work piece 20 at the other slide, and on two separate reverse strokes to respectively load and unload work pieces at the opposite slides, and power operated clamping means at each slide, comprising in combination, pumping means, a broaching motor, a 25 pair of clamping motors and a loading and unloading motor, means for controlling the supply of fluid to said motors, and an operating system for said control means to provide a continuous cycle of loading, clamping, broaching, 30 unclamping and unloading at each slide alternately, said operating system including means for initiating operation of the loading motor in response to operation of both a clamping motor and the broaching motor.

4. A hydraulic power transmission system for 40 operating a dual ram broach having a pair of power operated broach slides, a power operated loading and unloading device operable on two separate forward strokes to respectively load a work piece at one slide and unload a work piece at the other slide, and on two separate reverse strokes to respectively load and unload work pieces at the opposite slides, and power operated clamping means at each slide, comprising in combination, pumping means, a broaching motor, a 45 pair of clamping motors and a loading and unloading motor, means for controlling the supply of fluid to said motors, an operating system for said control means to provide a continuous cycle of loading, clamping, broaching, unclamping and unloading at each slide alternately, said operating system including means for initiating operation of the loading motor in response to operation of both a clamping motor and the broaching 50 motor, and means for alternately controlling the loading motor first from one clamping motor and then from the other.

5. A hydraulic power transmission system for 55 operating a dual ram broach having a pair of power operated broach slides, a power operated loading and unloading device operable on two separate forward strokes to respectively load a work piece at one slide and unload a work piece at the other slide, and on two separate reverse 65 strokes to respectively load and unload work pieces at the opposite slides, and power operated clamping means at each slide, comprising in combination, pumping means, a broaching motor, a pair of clamping motors and a loading and unloading motor, means for controlling the supply of fluid to said motors, and an operating system for said control means to provide a continuous cycle of loading, clamping, broaching, unclamping and unloading at each slide alternately, said 70 75

- operating system including means for initiating operation of clamping motor in response to operation of both the broaching motor and the loading motor.
5. A hydraulic power transmission system for operating a dual ram broach having a pair of power operated broach slides, a power operated loading and unloading device operable on two separate forward strokes to respectively load a 10 work piece at one slide and unload a work piece at the other slide, and on two separate reverse strokes to respectively load and unload work pieces at the opposite slides, and power operated clamping means at each slide, comprising in combination, pumping means, a broaching motor, a pair of clamping motors and a loading and unloading motor, means for controlling the supply of fluid to said motors, and an operating system for said control means to provide a continuous 15 cycle of loading, clamping, broaching, unclamping and unloading at each slide alternately, said operating system including means for initiating operation of each clamping motor in response to respectively opposite operations of both the broaching motor and the loading motor.
6. A hydraulic power transmission system for operating a dual ram broach having a pair of power operated broach slides, a power operated loading and unloading device operable on two 20 separate forward strokes to respectively load a work piece at one slide and unload a work piece at the other slide, and on two separate reverse strokes to respectively load and unload work pieces at the opposite slides, and power operated clamping means at each slide, comprising in combination, pumping means, a broaching motor, a pair of clamping motors and a loading and unloading motor, means for controlling the supply of fluid to said motors, and an operating system for said control means to provide a continuous 25 cycle of loading, clamping, broaching, unclamping and unloading at each slide alternately, said operating system including means for initiating operation of each clamping motor in response to respectively opposite operations of both the broaching 30 motor and the loading motor.
7. A hydraulic power transmission system for operating a dual ram broach having a pair of power operated broach slides, a power operated loading and unloading device operable on two 35 separate forward strokes to respectively load a work piece at one slide and unload a work piece at the other slide, and on two separate reverse strokes to respectively load and unload work pieces at the opposite slides, and power operated clamping means at each slide, comprising in combination, pumping means, a broaching motor, a pair of clamping motors and a loading and unloading motor, means for controlling the supply of fluid to said motors, and an operating system for said control means to provide a continuous 40 cycle of loading, clamping, broaching, unclamping and unloading at each slide alternately, said operating system including means for initiating operation of the broaching motor in response to operation of each clamping cylinder.
8. A hydraulic power transmission system for operating a dual ram broach having a pair of power operated broach slides, a power operated loading and unloading device operable on two 45 separate forward strokes to respectively load a work piece at one slide and unload a work piece at the other slide, and on two separate reverse strokes to respectively load and unload work pieces at the opposite slides, and power operated clamping means at each slide, comprising in combination, pumping means, a broaching motor, a pair of clamping motors and a loading and unloading motor, means for controlling the supply of fluid to said motors, and an operating system for said control means to provide a continuous 50 cycle of loading, clamping, broaching, unclamping and unloading at each slide alternately, said operating system including means for initiating operation of the broaching motor in response to operation of each clamping cylinder.
9. A hydraulic power transmission system for operating a dual ram broach having a pair of power operated broach slides, a power operated loading and unloading device operable to 55 respectively load a work piece at one slide and unload a work piece at the other slide, and to respectively load and unload work pieces at the opposite slides, and power operated clamping means at each slide, comprising in combination, pumping means, a broaching motor, a pair of clamping motors and a loading and unloading motor, means for controlling the supply of fluid to said motors, and an operating system for said control means to provide a continuous 60 cycle of loading, clamping, broaching, unclamping and unloading at each slide alternately, said operating system including means for initiating operation of the broaching motor in opposite directions in response to operation of each clamping cylinder alternately.
10. A hydraulic power transmission system for operating a dual ram broach having a pair of power operated broach slides, a power operated loading and unloading device operable to 65 respectively load a work piece at one slide and unload a work piece at the other slide, and to respectively load and unload work pieces at the opposite slides, and power operated clamping means at each slide, comprising in combination, pumping means, a broaching motor, a pair of clamping motors and a loading and unloading motor, means for controlling the supply of fluid to said motors, and an operating system for said control means to provide a continuous 70 cycle of loading, clamping, broaching, unclamping and unloading at each slide alternately, said operating system including means for initiating operation of the broaching motor in opposite directions in response to operation of each clamping cylinder alternately.
11. A duplex hydraulic broaching machine comprising a pair of alternately operative and oppositely moving broaching slides, a separate work support for each broaching slide, means to move said work supports simultaneously and 75

oppositely to loading and broaching positions, and clamping devices secured to the fixed frame of the machine and operative to engage and clamp a piece of work on a work support only after said support and work have been fully moved to broaching position.

14. A duplex hydraulic broaching machine comprising a pair of alternately operative and oppositely moving broaching slides, a separate work support for each broaching slide, means

to move said work supports simultaneously and oppositely to loading and broaching positions, devices to clamp the work on a work support only after said support and work have been fully moved to broaching position, and control devices operatively interlocking said work support and said clamping devices and automatically preventing movement of said work supports so long as either clamping device is operative.

HUGH C. NYE. 10
